UNITED STATES PATENT OFFICE.

CAMPBELL MURRAY HUNTER, OF LONDON, ENGLAND.

BURNER FOR COMBUSTIBLE GASES.

1,071,053.

Specification of Letters Patent.

Patented Aug. 26, 1913.

Application filed March 8, 1913. Serial No. 751,881.

To all whom it may concern:

Be it known that I, CAMPBELL MURRAY HUNTER, a subject of the King of the United Kingdom of Great Britain and Ireland, residing at London, in the county of Middlesex, England, have invented certain new and useful Improvements in Burners for Combustible Gases; and I do hereby declare the following to be a full, clear, and exact description of the invention, such as will enable others skilled in the art to which it appertains to make and use the same.

My invention relates more especially to the construction of gas burners of the inductor type, and has for its objects the utilization of either natural, producer, or coal gas under a widely varying range of pressure conditions, including vacua; and the thorough and intimate admixture of the gas with the air necessary for effecting complete combustion and the generation or production of a Bunsen flame of uniform intensity.

The burner is simple in form, economical in construction, and certain in operation.

To this end the main feature of my invention, generally stated, embraces the combination in a gas burner, of a gas chamber having a delivery nozzle, a helical blade or vane located in said nozzle, and a trumpet shaped mixing chamber having valve controlled air ports, said ports being circumferentially disposed with relation to the nozzle; also a centrally disposed steam jet designed to act as a powerful inductor or exhauster in cases where it is desired to draw the gas from a source at low pressure or to create a vacuum in the source of supply.

There are other, minor, features of invention, all as will hereinafter more fully appear.

In the drawings chosen for the purpose of illustrating this invention, the scope whereof is pointed out in the claims, Figure 1 is a longitudinal central section of a gas burner embodying my invention, Fig. 2 is a transverse section of the valve portion of the mixing chamber, the nozzle, and the helical blade or vane, taken in the plane of the line 2—2, Fig. 1, and Fig. 3 is a vertical transverse section of the gas chamber, steam

jet pipe, and stem of the needle valve, taken on the line 3—3, Fig. 1.

Like symbols refer to like parts wherever they occur.

I will now proceed to describe my invention more fully so that others skilled in the art to which it appertains may apply the same.

In the drawings, 1 indicates the gas chamber of the burner with which the gas supply pipe G connects. This gas chamber preferably is of the usual pear shape common to injectors, its outlet 1^a constituting a narrow throat leading to a delivery nozzle 1^b.

2 indicates the steam jet pipe with which the steam supply pipe S connects. This steam jet pipe 2 is centered with the throat or outlet 1^a of the gas chamber 1, and is controlled by the usual or any approved form of needle valve 3, the stem of which is threaded as at 3^a, where it passes through the rear wall of the gas chamber 1.

Any suitable means for manipulating the needle valve 3 may be provided. In the present instance a hand wheel 4 on the stem 3 is shown.

The gas chamber of the burner is shown as provided with threaded openings g and s for the reception of the threaded ends of the gas supply pipe G and the steam supply pipe S.

Located in the nozzle 1^b is a helical blade or vane 5 which may be of sheet iron twisted into a helix of any desired pitch, said helical blade or vane having for its function the imparting to the stream of gas, or steam, or gas and steam, issuing from the throat 1^a of the gas chamber 1 a whirling motion as it emerges from the nozzle 1^b.

6 indicates a trumpet shaped or flaring mixing chamber for the gas and air, the inner end of which chamber incloses the nozzle 1^b and is provided with a series of air ports 6^a for admission of the air which is to intermingle with the gas. The air ports 6^a are preferably of longitudinally tapering form, equally spaced circumferentially around the end of the trumpet shaped mixing chamber 6. In order to control said air ports 6^a, a rotary sleeve valve 7 is mounted on the rear

end of the mixing chamber 6, said valve having ports 7^a corresponding in size with the air ports 6^a of the mixing chamber, each of said ports guarded by a substantially tangentially disposed guide plate or flange 7^b, which, when ports 6^a are open, causes the entering air to assume a rotary motion in the same sense as the whirling gas stream emitted from nozzle 1^b.

10 The construction of the burner being substantially that hereinbefore pointed out, its operation will be as follows: Gas is first admitted from the gas supply pipe G into the gas chamber 1 of the burner and is ignited at the outer end of the trumpet. If the pressure of the gas as admitted to gas chamber 1 is insufficient in itself to cause the requisite amount of gas to flow through the burner steam is admitted from steam supply pipe S into steam jet pipe 2 and the needle valve 3 is manipulated to pass the amount of steam necessary to obtain the required velocity of flow in the gas passing from the gas chamber 1 through throat 1^a 25 into nozzle 1^b. The required velocity of flow in the gas being obtained, a rapidly whirling motion will be imparted thereto, in its passage through nozzle 1^b, by the helical blade or vane 5. This gyratory motion has 30 the multiple effect of causing, firstly, a thorough intermixture of the gas and steam, secondly, the throwing out from such mixture of any steam which may have become condensed and which would otherwise cool 35 the flame, thirdly, the subsequent and complete intermixture in chamber 6 of the gas, steam and induced air, which mixing is much aided by the differing specific gravities of the steam, gas and air. The air ports 40 6^a which, up to this time have been kept closed, are now gradually opened by the rotation of circumferential sleeve valve 7 until the flame assumes the desired character, and the point of ignition is located just beyond the mouth of the trumpet-shaped mixing chamber 6.

Owing to the substantially tangential position of the guide plates or flanges 7^b, the air currents entering at ports 6^a guided 50 thereby will have a direction or motion tangential to the axis of the burner and similar to that of the rotating current of gas or gas and steam which will facilitate and augment the induction of the air and its admixture with the gyrating current of gas in the mixing chamber.

As hereinbefore noted, my invention is applicable to burners for either natural, producer, or coal gas.

60 The burner will work effectively with gas at any pressure, and in cases where the pressure is sufficient for the gas to attain a high enough velocity to induce the necessary volume of air no steam is necessary.

The action of the burner will also be effective without steam wherever sufficient chimney draft is available to materially assist the flow of air through the air ports of the mixing chamber.

Where it is desired to utilize the burner 70 for burning natural gas from an oil or gas well, if the pressure of the gas is sufficient the steam induction jet need not be used, but, where the gas pressure is low, or as frequently happens, it is found desirable to 75 create a vacuum in the well to increase the production of the well, or for any other purpose, the steam jet may be employed and the burner will then act on the well as a very powerful exhaust.

80 When steam is used for induction purposes, a water or mercury pressure column as indicated at 8, Fig. 1, should be attached to the gas inlet pipe close up to the burner. in view of the fact that the burner is designed to maintain a very considerable suction in the gas pipe; and further, where two or more burners are drawing from the same main supply pipe, a delicate type of non-return valve should be provided in each of 85 the pipes leading to the respective burners, as indicated at 9, Fig. 1.

90 In order to obviate any danger from back-firing a gauze damper 10 may be inserted in the gas inlet pipe in any suitable manner.

95 The burner has incorporated with it as an integral part of itself a power producing apparatus capable of drawing the fluid fuel from a source below atmospheric pressure if necessary or desirable, and is distinct 100 from others inasmuch as it combines the functions of a gas burner with those of a gas exhaust or pumping device.

Having thus described my invention, what I claim and desire to secure by Letters Patent is:

1. A gas burner comprising a gas chamber having a contracted exit throat and a delivery nozzle leading therefrom, a helical blade or vane arranged in the nozzle, and a mixing chamber having at its rear circumferential valved air ports which surround the nozzle of the gas chamber.

110 2. A gas burner comprising a gas chamber having a contracted exit throat and a delivery nozzle, a steam jet delivering into the exit throat of the gas chamber, a helical blade or vane arranged in the nozzle, and a mixing chamber having at its rear circumferential valved air ports which surround 115 the nozzle of the gas chamber.

120 3. A gas burner comprising a gas chamber having a contracted exit throat and a delivery nozzle, a helical blade or vane arranged in the nozzle, a mixing chamber having at its rear circumferential valved ports which surround the nozzle of the gas chamber, and substantially tangentially disposed 125

guides for directing the air currents through the air ports of the mixing chamber.

4. A gas burner comprising a gas chamber having a contracted exit throat and a delivery nozzle, a steam jet delivering into the exit throat of the gas chamber, a helical blade or vane arranged in the nozzle, a mixing chamber having at its rear circumferential air ports surrounding the nozzle, and a 10 rotary valve sleeve having substantially tan-

gentially disposed guide flanges for directing air currents through the air ports of the mixing chamber.

In testimony whereof I affix my signature, in the presence of two subscribing witnesses. 15
